UNITED STATES PATENT OFFICE.

CARL MÜLLER, OF CHICAGO, ILLINOIS, ASSIGNOR TO MARDER, LUSE & CO.,
OF SAME PLACE.

DESIGN FOR A FONT OF PRINTING-TYPE.

SPECIFICATION forming part of Design No. 12,862, dated April 11, 1882.

Application filed November 18, 1881. Term of patent 7 years.

To all whom it may concern:

Be it known that I, CARL MÜLLER, of Chicago, in the county of Cook and State of Illinois, have invented a new and useful Design 5 for a Font of Printing-Type, which I have named "Program;" and I do hereby declare that the following is a full, clear, and exact description thereof, which will enable others skilled in the art to which it appertains to 10 make and use the same, reference being had to the accompanying specimens of printing, which form a part of this specification.

My new design consists of a font of printing-type in which the letters and numerals are provided with ceriphs, and all the upper and lower 15 case letters, the numerals, the ceriphs, and all the ornamental characters are formed entirely of light lines of equal and uniform thickness, and in which there are no angularities in the lines 20 usually curved, as shown in the accompanying printed specimens.

What I claim as new, and desire to secure by Letters Patent, is—

The new design for a font of printing-type in which the letters and numerals are provided 25 with ceriphs, and all the upper and lower case letters, the numerals, the ceriphs, and all the ornamental characters are formed entirely of light lines of equal and uniform thickness, and in which there are no angularities in the lines 30 usually curved, substantially as described and shown.

In testimony that I claim the foregoing as my own invention I affix my signature in presence of two witnesses.

CARL MÜLLER.

Witnesses:

JOHN MARDER,
A. P. LUSE.
